UNITED STATES PATENT OFFICE.

ERNST HURLIMANN, OF ZUCHWIL, SOLOTHURN, FREDERIC BILLON, OF SOLOTHURN,
AND JACQUES BOHLI, OF SOLOTHURN, OBACH, SWITZERLAND, ASSIGNORS TO THE
FIRM SCINTILLA, OF SOLOTHURN, SWITZERLAND.

CONDENSER FOR IGNITION APPARATUS.

Application filed October 18, 1919. Serial No. 331,735.

To all whom it may concern:

Be it known that we, ERNST HURLIMANN, a citizen of the Swiss Republic, residing at Zuchwil, Solothurn, Switzerland, FREDERIC BILLON, a citizen of the Swiss Republic, residing at Solothurn, Switzerland, and JACQUES BOHLI, a citizen of the Swiss Republic, residing at Solothurn, Obach, Switzerland, have invented certain new and useful Improvements in Condensers for Ignition Apparatus Used in Conjunction with Explosion Motors, of which the following is a specification.

This invention relates to an improved condenser for ignition apparatus of explosion motors.

The generation of the ignition voltage at the spark plugs of explosion motors is generally effected by the method of connection which is diagrammatically illustrated in Fig. 1. Alternating or pulsating current is electromagnetically produced in the primary coil *a*, which current is alternately closed over the interrupter *b* and the condenser *c*. The primary current impulses, which are strengthened by the condenser, induce into the secondary winding *d* voltage impulses which are sufficiently strong even in the case of low motor speeds to allow the ignition spark to jump over between the electrodes *e* of the spark plug. It is customary to place the condenser in the casing of the ignition machine, which casing, however, has to be kept as small as possible.

This is attained according to the invention in that the outer shape of the condenser is made to correspond to the form of the ignition coil.

Various forms of construction for carrying the invention into effect are illustrated by way of example, in the accompanying drawings in which Figure 1 represents diagrammatically a common arrangement of circuits in an ignition device. Figure 2

represents a cross-sectional view of an ignition coil and its condenser. Figure 3 is a sectional elevation of an ignition coil with the condenser wound between the primary and secondary windings, and Figure 4 a cross-sectional view of the coil illustrated in Figure 3.

Referring to Fig. 2, the condenser *c* is bent in the shape of a cylindrical segment corresponding to the form of the coil, and is placed around a portion of the outer surface of the coil *f*. The condenser is held by means of metal bands *g* against the two cross members *h*, which are secured between the insulating flanges *i* of the coil *f*.

Referring to Figs. 3 and 4, the condenser *c* is bent cylindrically corresponding to the form of the coil, but is arranged between the primary winding *a* and secondary winding *d* and placed in several layers round the primary coil *a*. Similarly the condenser may be wound outside around the secondary coil *d* or entirely inside around the iron core *k*. Sometimes it is sufficient to construct the condenser as a cylindrical condenser, that is with concentric and closed condenser coatings.

What we claim is:—

1. An ignition coil including a core, a primary and a secondary winding surrounding said core and a condenser, whose surface is in contact with the inner surface of one of said windings and conforms in shape thereto, surrounding said core.

2. An ignition coil comprising a cylindrical core, a coil surrounding said core, a condenser surrounding said coil and an outer coil surrounding said condenser.

In testimony whereof they have signed their names to this specification.

ERNST HURLIMANN.
FREDERIC BILLON.
JACQUES BOHLI.
